CORE DRILL

Robert S. Mann, Elyria, Ohio

Application June 27, 1940, Serial No. 342,817

8 Claims. (Cl. 255—72)

The invention relates to core drills and has as an object the provision of a drill of this character capable of use continuously to the end of obtaining a core during a complete drilling operation.

It is a further object of the invention to provide a drill having a core supporting means capable of removing a core of loose or friable material.

It is a further object of the invention to provide a drill having core-cut-off apparatus controllable from the drill rig floor.

It is a further object of the invention, in some forms thereof, to provide a drill having cut off apparatus operated by revolution of the drill when prepared for this action at will of the driller.

It is a further object of the invention to provide apparatus of this character that will tend to keep the wash fluid away from the core.

Further objects will appear from the following description showing illustrative embodiments of the invention and wherein—

Figure 1 is a central vertical section;

Figure 2 is a bottom plan view of a housing and core barrel connecting plate;

Figure 3 is a perspective view of a core-cutter way member;

Figure 4 is a perspective view of a core cutter;

Figure 5 is a central vertical section taken at right angles to the section of Figure 1;

Figure 6 is a detail plan view of the drill body of Figures 1 and 5 showing the core cutters and way member in place;

Figure 7 is a central vertical section of another form of the invention;

Figure 8 is a detail plan view of the cut-off mechanism and control means of the form of Figure 7;

Figure 9 is a perspective view of a cutter of the form of Figures 7 and 8, and

Figure 10 is a detail central vertical section, showing a still further form of the invention.

As shown in Figures 1-6 inclusive, the drill comprises a drill body 15 formed with an upstanding annular flange 16 shown as both externally screw threaded at 17 and internally screw threaded at 18. To the threads 17 there is shown connected a drill stem 19.

The drill body 15 is shown as terminating downwardly in drill teeth 20 and core cutting means 21. The form of drill and core cutting means shown is for purpose of illustration only. Any form of rigid teeth, rotary cutter, or diamond drill means may be adopted to be carried by the drill body.

The space within the annular flange 16 is utilized to house the cut-off mechanism and receives

the closure 21' formed with a core receiving bore 22 in axial alignment with bore 23 formed in the drill body 15, the closure 21' having external screw threads for coaction with internal threads 18.

To receive the core barrel 24 the closure 21 is shown as formed with an upstanding screw threaded nipple 25.

For reception of the core cutting mechanism 10 the closure 21 is shown as formed with a downwardly open recess 26, receiving a member 27 shown in perspective in Figure 3. To receive the cutters and core supporters 28, 29, the member 27 is shown as formed with dovetail way recesses 30, 31. For operation of the core cutters 28, 29, to the closing position shown in Figure 6, there is shown a fluid pressure conduit 32 communicating with a T-member 33, in turn communicating with conduits 34, 35, opening into sleeves 36, 37, slidably engaged in openings 38 in the bodies of the cutters.

When it is desired to sever a core for withdrawal a fluid pressure, preferably air, is applied to the conduit 32 which extends to the drill rig floor which fluid pressure, entering the sleeves 36, 37, forces the cutters 28, 29 toward each other. The said sleeves are closed at their outer ends and the ends abut against the wall of the recess 26.

30 During the cutting off operation with the cutters under influence of the fluid pressure, the drill is rotated without weight applied thereto so that the teeth 38', 39 upon the respective cutters will saw off the core as they are forced inwardly and rotated. When the cutters are closed as shown in dotted lines in Figure 6, they will make a substantially tight joint for the reason that they are formed complementary to each other so that the teeth of each cutter fit into the recess between teeth of the other cutter.

The apparatus may then be hauled out taking the core with it, and because of the tight closure of the cutters, and because the cutters stand below the entire lower surface of the core, the core will be removed in perfect condition even though the drilling is in a loose and friable formation.

50 To prevent the cutters from being displaced inwardly during the going in of the drill to working position there are shown spring pressed ball detents 40, 41 housed in recesses in the body of the annular disk portion of the member 27.

To supply drilling fluid used for the purpose of washing away chips produced in the drilling operation, the closure member 21' is shown as

formed with openings 42, 43, and the member 27 with openings 44, 45 to register therewith when assembled. To prevent undue leakage of the drilling fluid to the core barrel which might damage the core, the holes when assembled are shown as lined with sleeves 46, 47 having screw thread engagement with the closure 21. The sleeves and the openings containing the same are so placed as to terminate at an annular recess 48, which recess communicates with passages 49 to the zone of operation of the drill teeth, from which zone the drilling fluid will circulate upwardly exterior of the drill stem in the usual manner. The passages 49 are indicated as four in number.

In the form of the invention shown in Figures 7-9, the drill body is shown at 15', the core opening at 23', the core barrel at 24' and the drill stem at 19'. In this form of the invention the drilling fluid openings 42', 43' communicate with an annular recess 48', which in turn communicates with passages 49' to conduct the drilling fluid to the zone of operation.

The core body is shown as formed with an up-standing annular flange 16' having exterior threaded engagement with the interior of a ring 50 supplied for convenience in forming the drilling fluid openings 42'. The closure member 21' in this form of the invention also carries the up-standing nipple 25' for screw threaded engagement with the core barrel. For operation of the cutter and core supporting members 51-52, there is shown a revoluble ring 53 housed in the recess 26' in the closure member 21' and held in position by an overlying shoulder 54 formed in the recess. Seated in the recess 26' there is shown a disk member 55 having the outline shown in Figure 8, whereby to prevent revolution in the recess.

Pivoted upon the disk 55 by means of cap screws 56, 57 are the cutters 51, 52 which cutters are formed with similar recesses each presenting a cam surface 58 to the action of pins 59, 60, carried by the disk 53. It will be seen that starting from a normal position of the pins 59, 60, as shown in Figure 8, with the cutters 51, 52 in the position shown in dotted lines, rotation of the disk 53 to the left in said figure, or counterclockwise, will cause the pins to act upon the cam surface 58 to move the cutters to the dot-dash lines shown in said figure wherein the teeth 38', 39' will mesh, they being formed complementary to each other as with the form of the invention first described.

To cause revolution of the disk 53, there is shown a pair of springs 60, 61 each anchored at one end as at 62, 63 to the interior of the recess 26' and anchored at the other end as at 64, 65 to the lower surface of the disk 53. To prevent inward movement of the cutters until the cutting off operation is desired and thereby to prevent rotation of the disk 53, there is shown a sleeve 66, slidably in a recess 67 forming an enlargement of the bore 22' of the closure member 21'. The sleeve is shown in cutter locking position in Figure 7. When the cutting off operation is desired the sleeve 66 may be moved upwardly by a pull exerted upon a member 68 extending to the surface, which member is shown as terminating in a pin 69 secured to an arm 70 secured to the sleeve 66. All that is necessary in order to perform the cutting off operation, when it is desired to come out with the drill, is to exert a pull upon the member 68 and to rotate the drill without weight thereon. The core will be en-

tirely enclosed below, and supported by the cutters 51, 52 as in the form of the invention first described.

An alternative method of operating the cutters 5 of the first form of the invention by fluid pressure is indicated in Figure 10 comprising the insertion of a cartridge employing a slow burning explosive and which may occupy as much space in the sleeves as desired. To ignite the 10 explosive wire leads 71, 72 are shown which may be connected to a pair of wires leading to the floor of the drill rig. In the use of this form of mechanism the core cutters and supports 28', 29' are preferably formed with cutting edges 15 rather than with teeth, in order to more readily crack off rock or sever rock formation.

As stated, it is an object of the invention to provide a continuous production core drill. To this end the core barrel may extend to the drill 20 rig floor if desired. However the same end may be reached by providing a core barrel only long enough to accept a core of a length equal to the maximum distance that can be drilled without "coming out" for renewal or sharpening of the 25 drill. The shorter barrel should be capped at its upper end. This will trap air which air must be forced downwardly around the core as it enters the barrel, which fact will assist in excluding drilling fluid.

Friction between the stationary core and a revolving core barrel, at times results in breaking 30 of the core. To prevent this the invention includes the use of any well known form of swivel connection of the core barrel to the closure 35 member 21 or 21' in place of the screw threaded coupling shown.

Core drilling has an advantage for continuous 40 operation in that only an annulus requires to be worn away by the drill bit. A given weight on the bit and a given torque will therefore cause faster penetration. Such practice has been impossible heretofore since the core barrel of prior practice is too short and the core lifting means in common use has not been capable of supporting 45 a long core.

Minor changes may be made in the physical 50 embodiments of the invention within the scope of the appended claims without departing from the spirit thereof.

I claim:

1. A core drill comprising, in combination: a 55 drill body formed with an axial bore and having a chamber opening thereto; core cutting and supporting plates housed in said chamber normally in a position to leave said bore unobstructed; said plates movable to edgewise meeting engagement with each other to totally obstruct the bore; means to cause movement of said plates to core-cutting and supporting position 60 during normal operation of the drill; and means operable at the will of the operator to cause such closing movement of the plates.

2. The combination of claim 1 with complementary core cutting teeth carried by the respective plates, to provide a close joint therebetween, 65 said teeth acting to sever a core when moved thereagainst while the drill is rotated.

3. The combination of claim 1 with fluid pressure means to actuate movement of the plates and with means accessible to the operator to initiate the movement.

4. The combination of claim 1 in which the movement of the plates is caused by fluid pressure.

5. A core drill comprising, in combination: a

drill body having a core-receiving passage and a chamber opening into said passage adjacent its inlet opening; core severing and supporting plate means housed in said chamber clear of said passage during drilling operation; means mounting said plate means for movement in its own plane normal to the axis of said passage to core-severing and passage-obstructing positions and means to cause movement of said plate means in a plane fixed relative to the axis of the passage to said severing and obstructing positions at the will of the operator, the obstructing area of said plate means being substantially equal to the cross-sectional area of the core passage.

6. The combination of claim 5 with means operable from the drill rig floor during normal

revolution of the drill to initiate core-severing movement.

7. A core drill comprising, in combination: a drill body formed with an axial core passage and a chamber opening thereinto; a core cutting and supporting member housed in said chamber normally in a position to leave said passage unobstructed; a pressure cylinder adjacent said member; an explosive charge in said cylinder; electrical means to ignite the charge at will of the operator; and means whereby fluid pressure in said cylinder acts to move said member to passage obstructing position.

8. The combination of claim 7 in which the cylinder is normally housed in a recess in said member and slidably related thereto.
